BY Chas B. Mann
ATTORNEY.

UNITED STATES PATENT OFFICE.

JOHN HOFF, OF OWING'S MILLS, MARYLAND.

THILL-CO尤LING.

SPECIFICATION forming part of Letters Patent No. 439,245, dated October 28, 1890.

Application filed March 4, 1890. Serial No. 342,602. (No model.)

To all whom it may concern:

Be it known that I, JOHN HOFF, a citizen of the United States, residing at Owing's Mills, in the county of Baltimore and State of Maryland, have invented certain new and useful Improvements in Thill-Couplings, of which the following is a specification.

My invention relates to a certain improvement in thill-couplings, which is illustrated in the accompanying drawings.

Figure 1 is a side view of the device with the thill-iron, the bolt, and retaining-spring in position to hold the bolt. Fig. 2 is a side view of the clip portion with the thill-iron and bolt removed and the retaining-spring in the down position. Fig. 3 is a top view with part of the ears, the thill-iron, and retaining-spring shown in section and exposing the bolt. Fig. 4 shows two views of the retaining-spring. Fig. 5 is a view of the bolt. Fig. 6 shows a modification of the bolt, which is square adjoining the head.

The letter A designates the thill-iron, B the axle, and C the axle-clip with the ears a a' , each of which is provided with a bolt-hole b to receive the thill-bolt c . The bolt-hole b in one ear a is countersunk at its outer side b' to receive the head c' of the thill-bolt, which is thus allowed to be flush with the outer side 30 of the ear a . This same ear is provided with a thill-bolt retaining-spring d , part of which will normally cover the head c' of the bolt c , and thus keep it in place. One end of this

spring is secured to the side of the ear by a pivot f . The other end being free to swing, is 35 provided with a hole e , which engages with a pin e' , secured to the side of the ear a . The pin e' holds the retaining-spring d stationary when in position over the bolt-head c' .

The mode of operation is as follows: To take 40 out the thill-iron the free end of the retaining-spring d is drawn out of engagement with the pin e' and turned down to the position indicated in Fig. 2, thus uncovering the bolt-head and allowing the bolt to be drawn out 45 and the thill-iron removed from its position between the ears a a' . If it is desired to put the thill-iron into place, the reverse operation is used.

Having described my invention, I claim— 50

In combination, a thill-coupling having a thill-iron, an axle-clip with ears attached, one ear having at its side a pin e' , a coupling-bolt to hold the thill-iron, and a spring-plate in contact with the side of the ear which has the 55 pin and pivoted thereto by one end and the free end provided with a hole to engage with said pin, said spring-plate pressing directly against the head of the coupling-bolt, as shown and described. 60

In testimony whereof I affix my signature in the presence of two witnesses.

JOHN HOFF.
